UNITED STATES PATENT OFFICE.

ALTON N. GREGORY, OF SEATTLE, WASHINGTON.

TWINE-CUTTER.

1,379,864.

Specification of Letters Patent. Patented May 31, 1921.

Application filed August 26, 1920. Serial No. 406,193.

To all whom it may concern:

Be it known that I, ALTON N. GREGORY, a citizen of the United States, residing at Seattle, in the county of King and State of Washington, have invented a certain new and useful Improvement in Twine-Cutters, of which the following is a specification.

My invention relates to improvements in twine cutters and more particularly to the ring type of twine cutter which is adapted to be worn on the finger of the user and the object of my invention is to provide a twine cutter wherein the cutting edge of the knife or cutting element is disposed within an inwardly converging slot to thereby positively insure of the severing of the twine in a clean cut manner.

Another object is to provide a twine cutter that is adapted to cut twine, cord or thread of varying size and of any description.

A further object is to provide a twine cutter that embodies simplicity, durability and economy in construction, that is positive and efficient in operation, and that will not readily get out of order.

With the above and other objects in view which will appear as the description proceeds, my invention resides in the novel construction, combination, adaptation and arrangement of parts hereinafter described and claimed.

I accomplish these objects by devices illustrated in the accompanying drawings 35 wherein:—

Figure 1 is a view in side elevation of a twine cutter embodying the features of my invention.

Fig. 2 is a similar view of the same parts 40 being broken away to more clearly illustrate the disposition of the cutting element.

Fig. 3 is a view in vertical transverse section of my twine cutter taken on a broken line 3—3 of Fig. 1.

Fig. 4 is a fragmentary view in side elevation of a modified form of my twine cutter adapted for cutting twine of varying sizes, and

Fig. 5 is a view in top plan of the same. 50 Referring to the drawings throughout which like reference numerals indicate like parts, the numeral 10 indicates the ring or band portion of my cutter, the numeral 11 indicates a peripheral extension or lug 55 which may be integral with or otherwise

fixedly secured to the outer surface or back portion of the said ring, the said peripheral extension being disposed in the same medial plane as the ring 10 and being adapted to extend outwardly therefrom substantially as shown in the drawings.

Formed in the peripheral extension 11 and in tangential relation to the ring 10 is a rectangular recess or opening 12, the lower wall 13 of which is formed by the ring 10 60 and the upper wall 14 and the inner end wall 15 of the said recess being formed by the peripheral extension 11 as shown.

Medially disposed in the peripheral extension 11 is a knife or cutting element 16, the 70 said extension 11 being medially slit or cut in any suitable manner to receive the said knife 16. The cutting edge 17 of the said knife when the latter is positioned being adapted to project into the recess 12 as shown.

An inwardly converging groove 18 is provided in a lower wall 13 of the recess 12 as shown more clearly in Figs. 2 and 3, the said groove being adapted to receive the inner and lower portion of the cutting edge 80 17 of the knife 16 when the latter is operatively disposed in the extension 11 as shown in Figs. 2 and 3.

To positively retain the knife 16 in its operative position within the peripheral extension 11, the walls or jaws 19 which are formed by the medial slitting or cutting of the said extension are pressed together subsequent to the positioning of the knife 16 to thus clamp the said knife against movement 90 with respect to the said extension 11. However, the knife 16 may be riveted, soldered or otherwise secured in position if desired. But I have found in practice that by merely pressing the jaws 19 together against the 95 knife 16 that the latter is rigidly secured in operative position in a very simple and effective manner.

It will be obvious from the foregoing description and by referring to the drawings 100 that by disposing the inner end of the cutting edge 17 of the knife 16 in the converging groove 18, that a perfect cutting edge is at all times presented to the twine to be severed, that the ends of the cut twine are 105 cut clean and not left ragged as would occur if the cutting edge ended abruptly against the wall 13.

In the operation of my twine cutter the twine to be severed is inserted in the open 110

end of the recess 12 and brought into contact with the cutting edge 17 substantially at the angle shown in full lines in Fig. 1, the doubled end of the twine lying substantially 5 in the groove 18 during the cutting operation as will be obvious by referring to Fig. 3, the converging walls of the said groove 18 serving to guide the twine and hold the same against the cutting edge 17 to effect 10 a clean cut.

In the modified form illustrated in Figs. 4 and 5, I have shown a twine cutter adapted to cut twine of varying sizes, the said twine cutter comprising a ring or band 20 15 having an integral triangular peripheral extension 21, the sides 22 of which are tangentially disposed with respect to the periphery of the ring 20.

Pivottally mounted as at 23 in a medially 20 disposed groove 24 formed in the extension 21 is a cap or knife holder 25, the said knife holder being arranged for limited swinging movement with respect to the extension 21 as shown in full and dot and dash lines in 25 Fig. 4.

A flat spring 26 having its lower end riveted or otherwise fixedly secured to one of the sides 22 of the extension 21 is adapted 30 to have its upper or free end bear against the rear wall or face of the knife holder 25 to thereby retain the said holder in its normal or retracted position as shown in full lines in Fig. 4 or to return the said knife holder 25 to its normal or retracted position 35 from the advanced position shown by dot and dash lines in the said figure.

The shoulders 27 formed on the sides of the knife holder 25 are adapted to bear against the side 22 of the extension 21 when 40 the holder 25 is in its normal position to limit the downward movement of the same, while the squared portion 28 formed on the lower and outer end of the holder 25 is adapted to abut the lower wall 29 of the 45 groove 24 to limit the upward movement of the said holder as will be readily understood by referring to Fig. 4.

Medially disposed in the knife holder 25 in the forward portion thereof is a knife 50 or cutting element 30, the said holder being slit or cut in any suitable manner to receive and retain the said knife 30. The major portion of the cutting edge 31 of the knife 30 is adapted to be normally disposed in the 55 groove 24 as shown.

The knife 30 is secured in an operative position within the holder 25 in a similar manner as hereinbefore described for my preferred form.

In the operation of the modified form the 60 twine to be cut is inserted in the opening formed by the knife holder 25 and the side 22 of the extension 21, and brought in contact with the cutting edge 31, the said twine 65 during the cutting operation tending to raise the holder 25 against the relatively strong tension of the spring 26. However in the event that very heavy twine or cord is to be cut the holder 25 may assume the position shown in dot and dash lines in Fig. 4 70 in which position the lower and inner end of the cutting edge remains in the groove 24 to thereby present a perfect cutting edge when the knife holder 25 is in its most 75 advanced position.

The walls of the groove 24 may if desired be formed to converge inwardly in the same manner and for the same purpose as hereinbefore described for my preferred 80 form.

From the foregoing description taken in connection with the accompanying drawings, the advantages of the construction and of the method of operation of my improved twine cutter will be readily apparent to those skilled in the art to which my invention relates, but, while I have described the principle of operation of the invention, together with the structure which I now consider to be the best embodiment thereof, I desire to 90 have it understood that the twine cutter shown is merely illustrative and that such changes may be made when desired as are within the scope of the invention.

What I claim is:—

A twine cutter comprising a ring; an integral triangular peripheral extension formed on said ring, said peripheral extension having a longitudinal groove formed therein; a knife holder; a lug on said holder 100 adapted to pivotally connect said holder to said peripheral extension; shoulders on said lug adapted to contact with said extension to limit the swinging movement of said holder in a downward direction; a stop on 105 said lug adapted to contact with the bottom of said longitudinal groove to limit the swinging movement of said holder in an upward direction; a knife medially disposed in said holder having its cutting edge normally disposed in said longitudinal groove; and resilient means adapted to retain said knife holder in a normally retracted position.

In witness whereof, I hereunto subscribe 115 my name this 20th day of August A. D. 1920.

ALTON N. GREGORY.
